[57] CLAIM

The ornamental design for a hanger for a foam board, as shown and described.

DESCRIPTION

FIG. 1 is a front and right side perspective view of a hanger for a foam board showing our new design;
FIG. 2 is a top plan view thereof;
FIG. 3 is a front elevational view thereof;
FIG. 4 is a right side elevational view thereof;
FIG. 5 is a rear elevational view thereof;
FIG. 6 is a bottom plan view thereof;
FIG. 7 is a front, top and right side perspective view of a second embodiment thereof;
FIG. 8 is a front elevational view of the second embodiment;
FIG. 9 is a front, top and right side perspective view of a third embodiment thereof; and
FIG. 10 is a front elevational view of the third embodiment. The side, top, bottom and rear views of the second and third embodiments are substantially intelligible from the disclosures of FIGS. 7-10.
